UNITED STATES PATENT OFFICE

JAMES H. BUTRIDGE, OF CHICAGO, ILLINOIS, ASSIGNOR TO THE UNION SWITCH & SIGNAL COMPANY, OF SWISSVALE, PENNSYLVANIA, A CORPORATION OF PENNSYLVANIA

RAILWAY SIGNALING APPARATUS

Application filed May 5, 1931. Serial No. 535,115.

My invention relates to railway signaling apparatus, and particularly to apparatus for the signaling of stretches of single track over which traffic moves in both directions.

5 I will describe one form of apparatus embodying my invention, and will then point out the novel features thereof in claims.

In the accompanying drawings, Figs. 1^a and 1^b, when placed end to end with Fig. 10 1^a on the left, constitute a diagrammatic view showing one form of apparatus embodying my invention. Figs. 2^a and 2^b, when placed end to end with Fig. 2^a on the left, constitute 15 a diagrammatic view showing a modified form of apparatus also embodying my invention.

Similar reference characters refer to similar parts in each of the views.

Referring first to Figs. 1^a and 1^b, the reference character 29 designates a stretch of railway track over which traffic moves in both directions, which stretch is divided by the usual insulated joints to form blocks 1—2, 2—3 and 3—4. These blocks are further divided by insulated joints at points 5, 6 and 7, to form track sections 1—5, 5—2, etc. Each track section is provided with the usual track circuit comprising a track battery 30, and a track relay designated by the reference 30 character T with suitable distinguishing exponents and subscripts.

Traffic moving toward the left is governed by signals S¹, S², S³ and S⁴, while traffic moving toward the right is governed by signals S¹_E, S²_E, S³_E and S⁴_E. Each of these signals, as here shown, is of the light type, comprising three electric lamps G, Y and R, which lamps when lighted, indicate "proceed", "caution" and "stop", respectively. As here shown, each signal is located at the entrance end of one of the blocks, so that each block is provided with two signals governing traffic in opposite directions therethrough.

Associated with each signal S is a polarized home relay designated by the reference character H with the same exponent and subscript as those applied to the signal. Each signal is controlled in the usual manner by the associated home relay H. Referring particularly to signal S⁴, the circuit for the proceed

lamp G of this signal is from terminal X, of a suitable source of current, through the front point of neutral contact 27 of relay H⁴, polar contact 28 of this relay in the normal position, and lamp G to terminal O of the same source of current. The circuit for the caution lamp Y includes the front point of contact 27, and the polar contact 28 in the reverse position. The circuit for the stop lamp R includes the back point of neutral contact 27. It follows that the signal will indicate proceed when relay H⁴ is energized in the normal direction, caution when this relay is energized in the reverse direction, and stop when the relay is deenergized. The circuits for the lamps of the remaining signals are omitted from the drawing to simplify the disclosure, but it is understood that each signal is controlled by its associated relay H in the same manner that signal S⁴ is controlled by relay H⁴.

Associated with the home relay H⁴ is a polarized slow-acting relay A⁴, and a normally open stick relay B⁴. Similar relays A and B are provided for home relays H², H²_E and H³_E. The control of these relays A and B will be explained hereinafter.

Home relay H² is provided with a normal circuit which passes from the positive terminal of a battery K¹ at location 1, through the front point of contact 8 of home relay H¹, front contact 9 of track relay T¹_E, front contact 10 of track relay T², winding of relay H², and common wire O to the middle point of battery K¹. When this circuit is closed, home relay H² is supplied with current of normal polarity, so this relay is energized in the normal direction. When relay H¹ is open but the circuit for relay H² is closed at the track relay contacts, this circuit will pass from the negative terminal of battery K¹, through the back point of contact 8 of relay H¹, and thence as before through the track relay contacts and the winding of relay H². Under this condition, current of reverse polarity will be supplied to relay H², so that the relay will be energized in the reverse direction.

The normal circuit for relay H³ is from the positive terminal of battery K², through the

front point of contact 11 of relay H^2 , contact 12 of track relay T^2_E , back contact 13 of relay B^2_E , front contact 14 of track relay T^3 , winding of relay H^3 and common wire O to 5 the middle point of battery K^2 . When this circuit is closed, current of normal polarity is supplied to relay H^3 . When relay H^2 is open and relay B^2 is closed, the circuit for relay H^3 is from the negative terminal of battery K^2 , through front contact 22 of relay A^2 , front contact 21 of relay B^2 , back point of contact 11 of relay H^2 , contact 12 of track relay T^2_E , contact 13 of relay B^2_E , front contact 14 of track relay T^3 , winding of relay H^3 , 10 and common wire O to the middle point of battery K^2 . Under this condition current of reverse polarity will be supplied to relay H^3 .

The circuits for relay H^4 are similar to those for relay H^3 . That is to say, the normal circuit for relay H^4 passes from the positive terminal of battery K^3 and includes the front point of contact 15 of relay H^3 , contacts 16, 17 and 18 of relays T^3_E , B^3_E and T^4 , winding of relay H^4 and common wire O to 20 the middle point of battery K^3 . The reverse circuit for relay H^4 passes from the negative terminal of battery K^3 , and includes front contact 20 of relay A^3 , front contact 19 of relay B^3 , and the back point of contact 15 of relay H^3 , the remainder of the circuit being 25 the same as the normal circuit for relay H^4 . The circuits for the home relays H^1_E , H^2_E , H^3_E and H^4_E will be understood from the foregoing without specific explanations.

30 Each auxiliary relay A is normally supplied with current of normal polarity, so that its polar contacts are swung to the right. Referring to relay A^3 , the normal circuit is from the positive terminal of battery K^3 , through front point of contact 23 of relay H^3 , and the winding of relay A^3 to the middle point of battery K^3 . When relay H^3 becomes deenergized, current of reverse polarity is supplied to relay A^3 , the circuit being from the negative terminal of battery K^3 , through back point of contact 23 of relay H^3 , and the winding of relay A^3 to the middle point of battery K^3 . The circuits for the remaining relays A will be understood from the foregoing without detailed explanation.

35 Each relay B is provided with a pick-up circuit and a stick circuit. Referring particularly to relay B^3 , the pick-up circuit for this relay is from the negative terminal of battery K^3 , through back contact 36 of track relay T^3 , polar contact 24 of relay A^3 in the normal position, winding of relay B^3 , and common wire O to the middle point of battery K^3 . It will be seen that this circuit can be 40 closed when and only when track relay T^3 is open and the polar contacts of relay A^3 are in the normal position. In other words, it can be closed only during the interval between the opening of track relay T^3 , and the 45 response of the polar contacts of relay A^3 to

the deenergization of relay H^3 , and this interval will occur only when a train moving toward the left enters track section 6-3. The stick circuit for relay B^3 is from the negative terminal of battery K^3 , through polar contact 26 of relay A^3 in the reverse position, contact 25 of relay B^3 , and the winding of this relay to the middle point of battery K^3 . The relay B^3 is made sufficiently slow acting to bridge the time interval between the opening of polar contact 24 and the closing of polar contact 26 of relay A^3 .

The circuits for the remaining relays B are the same as those for relay B^3 , and will therefore be understood without further explanation.

The operation of the apparatus is as follows: Assuming that all parts of the apparatus are in the positions shown in the drawings, and that a train moving toward the right enters section 1-5, the consequent opening of track relay T^1_E will open the circuit for home relay H^2 at contact 9, and the opening of relay H^2 will open at the front point of contact 11 the circuit for relay H^3 . Similarly, the opening of relay H^3 will open at the front point of contact 15 the circuit for relay H^4 . It follows that relays H^2 , H^3 and H^4 will all be opened, with the result that signals S^2 , S^3 and S^4 will all indicate stop. Signal S^1 is not considered in the foregoing statement, because this signal will, of course, be controlled by apparatus to the left of point 1. As the train moving toward the right passes signal S^2 , this signal will return to the proceed position, and the same thing will occur as the train passes signals S^3 and S^4 .

I will now assume that a train moving toward the left enters section 7-4. The opening of track relay T^4 will open the circuit for relay H^4 , and also the circuit for relay H^3 . The opening of relay H^3_E will open relay H^2_E , and this will result in opening relay H^1_E . It follows that signal S^4 and all of the signals governing traffic toward the right will indicate stop. The opening of relay H^3_E will cause current of reverse polarity to be supplied to relay A^3_E , so that when the train enters section 3-7 and opens track relay T^3_E , the pick-up circuit for relay B^3_E will not be closed. When the train enters section 6-3, it will open track relay T^3 , and this will in turn open relay H^3 , so that signal S^3 will indicate stop, and current of reverse polarity will be supplied to relay A^3 . During the interval between the opening of relay T^3 and the response of the polar contacts of relay A^3 , the pick-up circuit for relay B^3 will be closed, and when the polar contacts of relay A^3 respond, the stick circuit for relay B^3 will become closed at contact 26. The reverse circuit for relay H^4 will now be closed at contact 19 of relay B^3 , contact 20 of relay A^3 and the back point of contact 15 of relay H^3 , so that relay H^4 will become ener- 133

gized in the reverse direction, with the result that signal S^4 will indicate caution. Signal S^3_E will indicate proceed as soon as the train leaves section 3-7. When the train enters section 2-6, it will cause no change in the condition of the apparatus other than to deenergize track relay T^2_E . It cannot close relay B^2_E because relay A^2_E is already in reverse position due to relay H^1_E being open. When the train passes signal S^2 it will cause this signal to indicate stop. It will also cause relay B^2 to become energized, thereby causing relay H^3 to become energized in the reverse direction, with the result that signal S^3 will change to the caution indication. The closing of relay H^3 will reverse the current supplied to relay A^3 so that the stick circuit for relay B^3 will become opened. The closing of relay H^3 will also close the normal circuit for relay H^4 so that signal S^4 will then change to the proceed indication. As the train passes signal S^1 , signal S^2 will change to the caution indication and signal S^3 to the proceed indication, and when the train leaves the point at which it influences relay H^1 , the parts of the apparatus will be restored to the conditions in which they are shown in the drawings.

The operation of the apparatus during the passage of a train moving toward the right will be understood from the foregoing without specific explanation.

Referring now to Figs. 2^a and 2^b, the apparatus shown in these views is the same as that shown in Figs. 1^a and 1^b, except for the circuits for certain of the home relays. The circuit for relay H^2 in Fig. 2^a is the same as the circuit for the same relay in Fig. 1^a. The circuit for relay H^3 in Figs. 2^a and 2^b, is, however, from the positive terminal of battery K^2 , through polar contact 40 of relay A^2 in the normal position, front neutral contact 41 of relay A^2 , front contact 12 of relay T^2_E , back contact 13 of relay B^2_E , front contact 14 of relay T^3 , and the winding of relay H^3 to the middle point of battery K^2 . The reverse circuit for relay H^3 is from the negative terminal of battery K^2 , through front contact 21 of relay B^2 , polar contact 40 of relay A^2 in the reverse position, front neutral contact 41 of relay A^2 , and then the same as before to the middle point of battery K^2 . It will be seen, therefore, that relay H^3 will be supplied with current of normal polarity when the track relays for block 2-3 are closed and relay A^2 is energized in the normal direction, whereas relay H^3 will be supplied with current of reverse polarity when these track relays are energized, and relay A^2 is energized in the reverse direction, provided that stick relay B^2 is closed.

Relay H^4 is controlled in a similar manner by polar contact 42 and neutral contact 43 of relay A^3 , as well as by front contact 19 of stick relay B^3 .

The circuits for relays H^1_E and H^2_E will be understood from the foregoing without detailed explanation.

It is believed that the operation of the apparatus shown in Figs. 2^a and 2^b will be clear from the foregoing explanation of the operation of the apparatus shown in Figs. 1^a and 1^b.

The present application is a continuation in part of my copending application, Serial No. 431,072, filed February 25, 1930, for railway signaling apparatus.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a stretch of single track divided into blocks, track circuits including track relays for said blocks, a signal for each block governing traffic in one direction through said stretch, a home relay for the control of each signal, a normal circuit for each home relay including front contacts of the track relays for the associated block and a front contact of the home relay for the block next in advance as well as a source of current of normal polarity, a normally open stick relay for each block, an auxiliary slow-acting polarized relay for each block, a circuit for each auxiliary relay supplied with current of normal or reverse polarity according as the associated home relay is closed or open, a pick-up circuit for each stick relay including a normal polar contact of the associated auxiliary relay and a back contact of the first track relay for the associated block, a stick circuit for each stick relay including a reverse polar contact of the associated auxiliary relay, and an auxiliary circuit for each home relay including front contacts of the track relays for the associated block and a back contact of the home relay for the block next in advance as well as a front contact of the stick relay associated with the latter home relay and a source of current of reverse polarity.

2. In combination, a stretch of single track divided into blocks, track circuits including track relays for said blocks, a signal for each block governing traffic in one direction through said stretch, a home relay for the control of each signal, a normally open stick relay and an auxiliary slow-acting polarized relay for each home relay, means for energizing each auxiliary relay in normal or reverse direction according as the associated home relay is closed or open, means for energizing each stick relay when the polar contacts of the associated auxiliary relay are in normal position and the first track relay of the associated section is open, means for

- keeping each stick relay energized while the polar contacts of the associated auxiliary relay are in reverse position, and means operating when all track relays of a section are closed to energize the associated home relay in normal direction if the home relay for the section next in advance is closed, and in reverse direction when the latter home relay is opened provided the stick relay associated therewith is closed.
3. In combination, a stretch of single track, signals governing traffic through said stretch in one direction, home relays for the control of said signals, means for controlling each home relay by a front contact of the home relay next in advance, track circuits including track relays for the control of said home relays, a normally open stick relay for each home relay, means operating when a stick relay is closed and the associated home relay is open to close an auxiliary circuit for the home relay next in the rear, an auxiliary slow-acting polarized relay for each home relay, means for supplying current of normal or reverse polarity to each auxiliary relay according as the associated home relay is closed or open, means for energizing each stick relay while the first track relay in advance is open and the associated auxiliary relay polar contacts are normal, and means for keeping each stick relay energized as long as the auxiliary relay polar contacts are reverse.
4. In combination, a stretch of single track, signals governing traffic through said stretch in one direction, home relays for the control of said signals, a normally open stick relay for each home relay, a normal circuit for each home relay including a front contact of the home relay next in advance, a reverse circuit for each home relay including a back contact of the home relay next in advance and a front contact of the stick relay associated with the latter home relay, and means for energizing said stick relays when a train passes through said stretch in said one direction but not in the other.
5. In combination, a stretch of single track, signals governing traffic in one direction through said stretch, home relays for the control of said signals, a normally open stick relay for each home relay, a normal circuit for each home relay including a front contact of the home relay next in advance and a source of current of normal polarity, a reverse circuit for each home relay including a back contact of the home relay next in advance and a front contact of the stick relay associated with the latter home relay as well as a source of current of reverse polarity, and means for energizing said stick relays when a train passes through said stretch in said one direction but not in the other.
6. In combination, a stretch of single track, signals governing traffic through said stretch in one direction, home relays for the control of said signals, a normally open stick relay for each home relay, a normal circuit for each home relay including a front contact of the stick relay associated with the latter home relay, an auxiliary relay for each home relay, means for energizing each auxiliary relay in normal or reverse direction according as the associated home relay is closed or open, means operating when a train moving in said one direction passes each signal for energizing the associated stick relay before the associated auxiliary relay reverses, and means for keeping each stick relay energized as long as the associated home relay is open.
7. In combination, a stretch of single track, signals governing traffic through said stretch in one direction, home relays for the control of said signals, a normally open stick relay for each home relay, a normal circuit for each home relay including a front contact of the home relay next in advance, a reverse circuit for each home relay including a back contact of the home relay next in advance and a front contact of the stick relay associated with the latter home relay, track circuits for the stretch for the control of said home relays, and means for energizing each stick relay when a train passes the associated signal moving in said one direction but not in the other.
8. In combination, a stretch of single track divided into blocks, track circuits including track relays for said blocks, a signal for each block governing traffic in one direction through said stretch, a home relay for the control of each signal, a normally open stick relay and an auxiliary slow-acting polarized relay for each home relay, means for energizing each auxiliary relay in normal or reverse direction according as the associated home relay is closed or open, means for energizing each stick relay when the polar contacts of the associated auxiliary relay are in normal position and the first track relay of the associated section is open, means for keeping each stick relay energized while the polar contacts of the associated auxiliary relay are in reverse position, and means for controlling each home relay by the track relays for the associated section and by the stick relay and auxiliary relay for the section next in advance.
9. In combination, a stretch of single track divided into blocks, track circuits including track relays for said blocks, a signal for each block governing traffic in one direction through said stretch, a home relay for the control of each signal, a normally open stick relay and an auxiliary slow-acting polarized relay for each home relay, means for energizing each auxiliary relay in normal or reverse direction according as the associated home relay is closed or open, means operating when a train moving in said one direction passes each signal for energizing the associated stick relay before the associated auxiliary relay reverses, and means for keeping each stick relay energized as long as the associated home relay is open.

direction according as the associated home relay is closed or open, means for energizing each stick relay when the polar contacts of the associated auxiliary relay are in normal position and the first track relay of the associated section is open, means for keeping each stick relay energized while the polar contacts of the associated auxiliary relay are in reverse position, and means operating when all track relays for a section are closed to energize the associated home relay in normal direction if the auxiliary relay for the section next in advance is energized in normal direction, and in reverse direction if such auxiliary relay is energized in reverse direction provided the stick relay associated therewith is closed.

In testimony whereof I affix my signature.
JAMES H. BUTRIDGE.
